UNITED STATES PATENT OFFICE.

WILLIS G. DODD, OF SAN FRANCISCO, CALIFORNIA.

WATER-WHEEL.

SPECIFICATION forming part of Letters Patent No. 401,484, dated April 16, 1889.

Application filed July 28, 1888. Serial No. 281,326. (No model.)

To all whom it may concern:

Be it known that I, WILLIS G. DODD, of the city and county of San Francisco, State of California, have invented an Improvement in 5 Water-Wheels; and I hereby declare the following to be a full, clear, and exact description of the same.

My invention relates to that class of water-wheels in which buckets placed upon the rim 10 of the wheel receive the impact of a stream of water discharged under head or pressure from a nozzle, said wheels being known by the name of "hurdy-gurdy;" and my invention consists in the constructions and combinations of devices which I shall hereinafter 15 fully describe and claim.

Referring to the accompanying drawings for a more complete explanation of my invention, Figure 1 is a perspective view of one of 20 my buckets. Fig. 2 is a side elevation of my wheel with buckets attached. Fig. 3 is a vertical cross-section of same.

The bucket A is formed with two pockets, a, side by side, and divided by a wall, a'. 25 These pockets are hemispherical, their concave faces being as perfectly of this shape as a small cutting away at a² of the ends of the edge of the division-wall will permit, this cutting away being to prevent a flat surface at 30 the ends of the said wall. Their convex backs are also as near hemispherical as their connection and the formation of the securing-flange B will allow. The intention is to make the concave faces of the pockets as nearly hemispherical as possible, and they are so throughout the greater portion of their area.

C is the wheel-shaft.

D is the hub of the wheel, having a flange, d.

E are the two annular disks, which are 40 riveted at e to the hub-flange d. Between these spaced or separated disks, at their outer edges, are riveted at b, the flanges B of the buckets A, being set in directly against and abutting on each other and forming, practically, a continuous solid ring, which effectually 45 prevents any bucket from working loose. The faces of the disks are solid, as shown in Fig. 2.

F is the nozzle through which the stream of water under head or pressure passes and by 50 which it is directed against the buckets. The stream strikes the edge of the division-wall

a', and, splitting after impact, enters the hemispherical pockets, and the water is then discharged over the edges of said pockets.

It is of prime importance in this class of 55 wheels that a perfect discharge of the water be had, no matter in what position the bucket may be. In the buckets now in use there is some one point where the water reacts upon itself. Where the impact surface is a flat 60 one, this point is directly at the moment of impact. Where the surface is an inclined one, the water is directed against some other portion of the bucket and splashes. In either case "dragging" is the result, the 65 splash interfering with the back of the succeeding bucket. The face of the bucket must be curved in every direction, and I have found by experiment that the curve must be equal in all directions. This can only be obtained by a perfect hemispherical bucket, 70 which provides for a perfect discharge of the water in any and all directions, no matter in what position or at what inclination the bucket may be. This avoids splashing and 75 consequent dragging.

As a double bucket with a stream-splitter has been found to possess advantages over a single bucket, I have constructed my bucket with the hemispherical pockets side by side 80 with the divisional wall for the purpose of receiving the impact and splitting the stream.

I am aware of the scoop-shaped buckets in this class of water-wheels and of the buckets having partially-curved and partially-flat 85 faces and of the buckets having a curve in one direction. I am also well aware of the bucket having a prow-shaped impact front, curving the water to each side, and especially am I aware of the double bucket having a division-wall with a pocket on each side; but none of these involves the feature of my invention. The flat impact surfaces obviously cannot have the same mode of operation, for the water reacts on itself at the moment of impact. The scoop-shaped and other partially-curved buckets do not discharge their water in all directions at all times equally. The prow-shaped bucket and the double split buckets are both bounded by straight inclined surfaces, and the water is directed on reaction against these surfaces and splashes. 95 100

I do not claim herein a double bucket with splitting wall; but I do claim an improved shape in this sub-class.

The construction of the body of my wheel 5 as shown, with the solid disks and the buckets secured between their edges, obviates all the difficulty known as "fanning." No currents of air are created to retard the motion of the wheel. The shape of the buckets as 10 consists in this result, for their form is such as to offer but slight resistance to the air. The wheel is strong, light, perfectly balanced, and the buckets are secured to the best advantage, which is a matter of great importance when 15 wheels are used under high heads of water.

Having thus described my invention, what I claim as new, and desire to secure by Letters Patent, is—

1. A water-wheel consisting of the combination of a hub having a central encircling flange, annular separated disks secured to the flange of the hub, and buckets formed with two pockets side by side, having hemispherically-concaved faces separated by a central

division-wall for receiving and splitting the 25 stream, said buckets having flanges secured between the outer edges of the disks, substantially as described.

2. A water-wheel consisting of the combination of a hub having a central encircling 30 flange, annular separated disks secured to the flange of the hub, and buckets having flanges secured between the outer edges of the disks, substantially as herein described.

3. A water-wheel consisting of the combination of a hub having a central encircling 35 flange, annular separated disks secured to the flange of the hub, and buckets with flanges seated and secured between the outer edges of the disks, said flanges abutting against 40 each other and forming a continuous ring, substantially as herein described.

In witness whereof I have hereunto set my hand.

WILLIS G. DODD.
